UNITED STATES PATENT OFFICE.

GEORGE G. TINDALL, OF OAKLAND, CALIFORNIA.

STEAM-BOILER.

SPECIFICATION forming part of Letters Patent No. 325,027, dated August 25, 1885.

Application filed February 27, 1885. (No model.)

To all whom it may concern:

Be it known that I, GEORGE G. TINDALL, of Oakland, in the county of Alameda and State of California, have invented a new and 5 Improved Steam-Boiler, of which the following is a full, clear, and exact description.

The object of my invention is to improve the construction of steam-boilers, and more especially boilers of that class in which straw 10 or like light substance is used for fuel, such as the boilers of steam-power thrashing-machines.

The invention consists in the construction and arrangement of parts, as will be herein- 15 after fully described and claimed.

Reference is to be had to the accompanying drawings, forming part of this specification, in which similar letters of reference indicate corresponding parts in all the figures.

20 Figure 1 is a central longitudinal sectional elevation of my improved steam-boiler. Fig. 2 is a vertical cross-sectional elevation of the boiler taken on the line x x , Fig. 1; and Fig. 3 is a rear end view of the boiler.

25 The letter A indicates the main shell of the boiler, which, above the fire-box B, has about a cylindrical cross-sectional form, and is fitted with the ordinary fire-tubes, C, which extend clear through from the front head-plate, D, 30 to the rear head-plate, E, of the boiler.

35 Back of the fire-box B the boiler-shell A is carried downward so it incloses the larger lower fire-tubes, F, which open into the fire-box, and, like the tubes C, extend clear through the rear end plate, E, of the boiler. The 40 boiler-shell A thus has an oblong shape from the fire-box B to its end plate, E. (See Figs. 1 and 3.)

I make the boiler-shell A preferably with 45 the upper plate, a, which extends from end to end of the boiler, and downward at each side, and a lower plate, a', which extends from the outer back plate, b, of the fire-box B to the rear end of the boiler and is riveted to the edges of the upper plate, a, and to the internal flange of the rear head, E, and to the out-turned flange of the fire-box plate b. The front head or plate, D, extends to the bottom of the water-leg or fire-box of the boiler, as at 50 D', Fig. 1.

As shown in Figs. 1 and 2, the fire-box B is built up of opposite inner side plates, b' b',

with outer side plates, b' b', spaced from plates b' b' to provide the usual water-circulation, and front and rear end plates, b' b', the forward ends of the lower-fire tubes, F, being set or expanded into the rear end plate, b'. The lower ends of the plates D' b' b' b' are fastened to the base-frame b' of the fire-box. 55

The upper ends of the plates b' b' are flanged, 60 preferably, outward from the interior of the fire-box, to which flanges are riveted at a' the front and rear edges of the downwardly-curving plate A', which also is riveted at a' to the top edges of the opposite side plates, b', and 65 the opposite side parts of the plate A', curve outward and upward to the point or place of connection of the main upper plate, a', with the opposite outer side plates, b' b', of the fire-box, where the plates a' b' A' are riveted 70 together at a' a', as shown in Fig. 2.

It will be seen that the plate A' forms the lower part of the shell A above the fire-box, and also the crown-sheet of the fire-box, and as the plate A' curves downward it is made 75 self-bracing by its form, so that no stay-bolts are required for it, as are necessary with the flat or almost flat crown-sheet plates of fire-boxes of the usual construction in boilers of this class, and by curving the crown-sheet A' 80 downward toward the center more room is given for the insertion of a larger number of long fire-tubes C for increasing the heating-surface of the boiler. It will be seen that the crown-sheet A' may be riveted to the inner 85 walls of the fire-box as a separate structure, which may afterward be riveted to the main body of the boiler, thus facilitating the construction of the boiler.

Stay-bolts H are run horizontally across the 90 boiler between the tubes C and about at the central part of the oblong portion of the boiler behind the fire-box B to brace this part of the boiler-shell, which naturally is weaker than the cylindrical part of the shell above the fire-box, and the lower row of braces H will range 95 along the joints of the plates a' a' at the opposite sides of the boiler.

Front and rear smoke-bonnets of any approved kind will be fitted over the head-plates 100 D E of the boiler, as indicated by the dotted lines I J, respectively, in Fig. 1, and so that products of combustion will pass from the fire-box B rearward through the larger fire-tubes

F, and then forward through the fire-tubes C to the smoke-stack fitted to the smoke-bonnet I.

5 The fire-box B has a feed-opening, K, which may or may not have a door fitted to it, and through which opening the straw fuel is passed into the fire-box.

10 The fire-grate consists of a series of tubes, L, closed at their inner ends and fitted at their outer open ends into the inner opposite side walls, b', of the fire-box, and preferably in pairs set in line across the fire-box, and so that the water may enter the grate-tubes to prevent burning out of the tubes. The closed ends of 15 the tubes lie quite closely to each other. (See Fig. 2.)

20 To provide for cleaning the interior of the grate-tubes without removing them, I fit suitable plugs, preferably screw-plugs M, in the outer walls or plates b' of the fire-box opposite each of the tubes L, and so that the plugs may be removed at any time to reach the interior of tubes L from the outside of the boiler.

25 I arrange the grate-tubes L in a horizontal series, L', and a vertical series, L'', and so that the tubes at L' will support the straw fuel above the bottom of the fire-box, and the tubes L'', by their disposal in front of the open ends of fire-tubes F, will prevent the fuel from being drawn in bulk against or into these tubes, whereby choking up of the tubes will be prevented, and an efficient draft may be maintained to insure the most perfect and economical combustion of the fuel.

30 35 Beneath the steam-discharge pipe N of the boiler, and a short distance from the top of the shell-plate a, I fix a plate, O, which extends or

40 arches over from one side of the boiler to the other, and reaches a considerable distance lengthwise of the boiler each way from the outlet N. The object of the plate O is to prevent the water in the boiler from passing out of the pipe N with the steam, or, in other words, to prevent priming.

45 I do not claim the hollow grate bars nor the plate O in this application, reserving the right to file separate applications therefor.

Having thus described my invention, I claim as new and desire to secure by Letters Patent—

50 1. In a steam-boiler, the combination, with the vertical spaced walls of the fire-box, of the downward-curved crown-sheet secured at or near its edges to the upper edges of said walls, the fire-tubes C F, and the outer upper U-shaped section, a, riveted at a' to the outer 55 wall and to the crown-sheet, said crown-sheet forming the bottom of the forward end of the boiler, substantially as set forth.

55 60 2. A fire-box steam-boiler shell constructed with upper plate or plates, a, lapping down its sides, lower plate or plates, a', riveted to the rear outer plate, b, of the fire-box, and to plates a and rear head, E, a front head, D, extended at the front of the fire-box B, which consists of inner plates, b' b' b'' b'', and a concavo-convex plate, A', riveted to the fire-box plates and to the plates a, and constituting the crown-sheet of the fire-box, substantially as herein set forth.

65 GEORGE G. TINDALL.
